(57) **CLAIM**

The ornamental design for diamond forming a cross, as shown and described.

DESCRIPTION

FIG. 1 is a top view of a diamond forming a cross showing my new design;

FIG. 2 is a side view, the other side being symmetrical; and, FIG. 3 is an end view, the other side being symmetrical. The broken line showing is included for the purpose of illustrating environmental matter and forms no part of the claimed design.

1 Claim, 2 Drawing Sheets

FIG. 1

FIG. 2

FIG. 3
